DESIGN FOR A CAP.

Application filed March 1, 1926. Serial No. 16,710. Term of patent 14 years.

To all whom it may concern:

Be it known that I, JOHN C. SUTTON, a citizen of the United States, residing at Rockford, in the county of Winnebago and State of Illinois, have invented a new, original, and ornamental Design for Cap, of which the following is a specification, reference being had to the accompanying drawing, forming part thereof.

The invention comprises a skeleton cap characterized by a visor, band and spider top, embodying inserts, such as for instance celluloid, bound by a bordering edge pre-

senting contrasting appearances between the inserts and edging.

In the drawing, wherein I have represented by surface shading the sheen of the celluloid inserts—

Figure 1 is a side view of a cap, showing my new design; and

Figure 2 is a front view thereof.

I claim:

The ornamental design for a cap, substantially as shown and described.

JOHN C. SUTTON.
